CEILING PANEL SUPPORT FRAME

Harold G. Blum, Palatine, Ill., assignor, by mesne assignments, to Koller Craft Plastic Products, Inc., Fenton, Mo., a corporation of Missouri

Filed May 27, 1969, Ser. No. 17,387

Term of patent 14 years

Int. Cl. D25—01
U.S. Cl. D13—1

FIG. 1 is a bottom perspective view of a ceiling panel support frame of this invention, showing in phantom a surrounding portion of a ceiling structure in which it is adapted to be used;

FIG. 2 is an enlarged perspective view of the ceiling panel support frame of FIG. 1;

FIG. 3 is a bottom view of FIG. 2;

FIG. 4 is a plan view of FIG. 2;

FIG. 5 is an enlarged partial side elevation of FIG. 2; and

FIG. 6 is a side sectional view of FIG. 2.

I claim:

The ornamental design for a ceiling panel support frame, substantially as shown and described.
